(Model.)

W. R. BARTON.
Edge Plane.

No. 236,759.

Patented Jan. 18, 1881.

UNITED STATES PATENT OFFICE.

WILLIAM R. BARTON, OF BRIDGEWATER, MASSACHUSETTS, ASSIGNOR OF
ONE-HALF TO GEORGE C. HAMMOND, OF CENTRAL FALLS, R. I.

EDGE-PLANE.

SPECIFICATION forming part of Letters Patent No. 236,759, dated January 18, 1881.

Application filed November 24, 1880. (Model.)

To all whom it may concern:

Be it known that I, WILLIAM R. BARTON, a citizen of the United States, residing at Bridgewater, in the county of Plymouth and 5 State of Massachusetts, have invented new and useful Improvements in Edge-Planes, of which the following is a specification.

This invention relates to an improvement in edge-planes which are adjustable for operation upon edges of different thickness. Its 10 objects are to simplify the construction of such tools, to render them more convenient for use than heretofore, to enable the cutting-edges to be kept sharp throughout and in condition for 15 work upon the edges to which they are especially adapted, and to secure uniformity of finish to the edges of any number of soles.

An adjustable edge-plane has been heretofore provided with a cutting-bit having one 20 finishing lip or flange stationary and the other adjustable, so that the extent of cutting-edge of the bit between the finishing lips or flanges may be varied to suit edges of different thickness. It is difficult to keep the bit of such a 25 tool in proper order, for when it has been used upon a sole of a given thickness a portion of the cutting-edge is thereby dulled, and the entire edge must be ground to uniformity before it can be used upon a thicker sole, and 30 even when used for a long time upon a comparatively narrow sole a great portion of the edge of the bit must be ground and reground without being used, in order to keep it in its original shape. Besides, it is quite difficult to 35 again adjust the movable lip to the exact gage of a class of soles upon which it has been previously used, so that there is a liability to be a lack of uniformity in edge-finish between the soles of two lots of shoes when uniformity 40 is desirable. Further, when the tool is in use the unused portion of the bit and its holder projects outward beyond the edge of the sole and prevents the operator from having a good view of his work.

45 In accomplishing its objects and remedying the defects of the old style of tool, as above set forth, my invention consists in a base-plate adapted to be connected with a suitable handle, and provided at one edge or side with 50 a vertical stationary jaw, the base-plate serv-

ing to receive and support a movable jaw, which is capable of lateral adjustment in relation to the stationary jaw, both of said jaws being provided with means for holding the longitudinal edges of bits of varying width. 55

It also consists in a novel construction and arrangement of a throat-piece to co-operate with different-sized bits, and in certain novel constructions and arrangements of devices whereby the various parts of the plane are 60 properly adjusted, and which will be hereinafter particularly described.

In the accompanying drawings, Figure 1 is an inner side view of an edge-plane constructed according to my invention. Fig. 2 is a front view of the same. Fig. 3 is an outer side view. Fig. 4 is a rear view. Fig. 5 is a perspective view of the bit and the several portions of the bit-holder and gages detached.

The letter A designates the handle, and B 70 the stationary portion of the bit and gage holder. This stationary portion consists of a base-plate, b, having at one end a lug, c, projecting at a right angle, and provided with a screw-hole, while the other end of said plate 75 is bent slightly in the same direction as the lug, and has a transverse oblique-bottomed guide-groove, d, formed across its inner surface, and a slot, e, cut through from said groove, the outer surface of the end of the plate being 80 beveled to form a seat for the head of a screw which passes through said slot, and which will be hereinafter referred to. From one side of the plate b, at its grooved and slotted end, a stationary jaw, f, projects at a right angle, 85 and has its upper edge provided with an undercut lip, g, this stationary jaw and its undercut lip forming the stationary portion of the bit-holder.

The letter f' designates a movable jaw, having 90 its upper edge provided with an undercut lip, g', similar to that of the jaw f, and its lower edge is formed to fit transversely in the groove d and extend across the upturned edge of plate b. The lower portion of the jaw f' is 95 thickened in order that it may be tapped with a screw-hole to receive a suitable-sized screw, h, which, when said movable jaw is arranged with its lower edge in the groove and across the end edge of the plate, passes through the 100

slot *e* and into said hole for the purpose of securing the movable jaw in any position to which it may be adjusted. The jaws *f* and *f'* are provided with coincident holes *i* *i'*, the hole 5 *i'* in the movable jaw being screw-threaded to engage the screw *k*, and the hole *i* in the stationary jaw being smooth and of proper size to let the shank of said screw pass loosely through it. The parts being thus placed, the 10 movable jaw may be adjusted to or from the stationary jaw by turning the screw as required.

The letter *L* designates a bit having a cutting-edge, *l*, and side-finishing flanges *m* *m*, 15 which, as is well known, may have any transverse contour desired. The outer edges of these flanges are beveled to fit under the undercut portions of the lips *g* and *g'* of the jaws *f* *f'*, and the bit will be firmly held by said 20 lips when its edges are placed thereunder, as shown clearly in Fig. 4, and the movable jaw properly adjusted and secured. Bits of different widths may be used, according to the thicknesses of the edge to be planed; and, as will 25 be seen, said bits may be adjusted longitudinally, according to the cut desired, and to compensate for the wear of the cutting-edges. Each bit and its flanges being made in one piece, it is obvious that a uniform finish is produced upon all edges upon which a given bit 30 is used; and though removed and replaced, its work will be the same, no adjustment of the extent of its cutting-edge being required; and being of proper width for its special work, there 35 will be no portion projecting outward beyond the sole and obstructing the operator's view of the work.

The longitudinal adjustment of the bit is made with respect to a throat-piece, *N*, the working-40 face of which corresponds approximately in transverse contour with that of the bit, and is provided with a stationary flange, *n*, which corresponds to the flanges of the bit which rests upon the stationary jaw *f*. The other flange, 45 *o*, of the throat-piece is adjustable, and is provided at its outer end with a slotted lug, *o'*, extending at an angle therefrom and resting upon

a shoulder, *p*, of the throat-piece, upon which it is adjustable, a screw, *p'*, passing through the slot of said lug and into the throat-piece, 50 serving to hold it in position, and permitting its adjustment to bring the flange *o* into coincidence with the corresponding flange of the bit used. The inner surface of the lower portion of the throat-piece is recessed to embrace the lug *c* of the plate *b*, which lug thus serves as a guide upon which the throat-piece is adjustable, and to which it is secured by means of a screw, *q*, passing through a slot, *q'*, in its 55 said lower position, and into the screw-hole *c'* of the lug. When a bit of the desired width is secured between the jaws the throat-piece is to be adjusted to fix the proper cut, and then the flange *o*, by moving the lug *o'*, is brought to coincide with the corresponding 60 flange of the bit.

What I claim is—

1. In an edge-plane, the combination, with a base-plate adapted to be connected to a handle and provided at one side with a vertical stationary jaw, of a vertical movable jaw capable of adjustment on the base-plate in relation to the stationary jaw, both of said jaws being provided with means for holding the longitudinal edges of bits of varying width, 75 substantially as described.

2. In an edge-plane, the combination, with the throat-piece provided with the stationary flange and an adjustable flange, of devices for holding bits of different widths, substantially 80 as described.

3. The combination, with the base-plate *b*, provided with the lug *c*, groove *d*, and stationary jaw *f*, having the undercut lip *g*, of the adjustable jaw *f*, having a similar undercut lip, 85 and the adjustable throat-piece and adjustable flange, substantially as described.

In testimony whereof I have hereunto set my hand in the presence of two subscribing witnesses.

WILLIAM RANDAL BARTON.
